United States Patent Office.

WILLIAM SAILER, OF PHILADELPHIA, PENNSYLVANIA.

Letters Patent No. 96,971, dated November 16, 1869.

IMPROVEMENT IN CLAMP.

The Schedule referred to in these Letters Patent and making part of the same.

I, WILLIAM SAILER, of Philadelphia, county of Philadelphia, State of Pennsylvania, have invented an Improved Joist-Clamp, of which the following is a specification.

Nature and Object of the Invention.

My invention consists of a clamp, so constructed and arranged for attachment to a joist, that none of the usual expensive screws or other fastenings are required, and so that it may be adapted to joists of varying widths, without changing the angle of that portion of the clamp between which, and the flooring-boards, the tightening-wedges are driven, all of which will be fully described hereafter.

Description of the Accompanying Drawing.

Figure 1 is a perspective view of my improved joist-clamp;

Figure 2, a plan view of the same; and

Figure 3, an end view.

General Description.

A (figs. 2 and 3) represents, in dotted lines, a portion of a joist or beam;

B B', my improved clamp, arranged to be firmly attached to the same;

C C, the flooring-boards; and

a, a wedge which is driven between the said clamp and boards, for the purpose of forcing the latter tightly together before they are nailed to the joist.

The clamp consists of a solid frame, B, of cast-iron, of the peculiar form shown in the drawing, and of an arm, B', of wrought-iron, hinged to one end of said frame by a bolt, c, this arm being furnished with several holes f f, through any one of which the pivoting-bolt may be inserted, according as it is necessary to increase or diminish the length of the said arm.

At one end of the frame B is an enlargement or head, h, the face i of which is inclined at about the angle shown in fig. 2, so that it may best adapt itself to the form of the wedge a which is driven between the said head and the flooring-boards.

A row of teeth, k, extends along one entire edge of the frame B, and beneath its projecting head h, and to the outer end of the arm B' is pivoted a self-adjusting block, l, which has serrations or teeth, m, on its inner side, corresponding to the teeth k.

In using the above instrument, the arm B', and projecting portion of the head h, rest upon the upper edge of the joist, so that the teeth k and m are

brought in contact, or nearly so, with the opposite sides of the said joists.

The pressure which is exerted against the head h, in driving a wedge between the same and the flooring-boards, has a tendency to force the frame B backward to a slight extent, and laterally toward the joist, and to turn the arm B' in the direction of the arrow. This will force the block l of the said arm more firmly against the joist, and will cause its teeth m, as well as the opposing teeth k of the frame, to bite into the opposite sides of the joist, and to firmly hold the clamp.

If the clamp is to be attached to a wider or narrower joist than that shown in the drawing, the length of the arm B' must be increased or diminished accordingly, its holes f permitting such adjustment.

The block l may be square or of any convenient shape, and may, if desired, be permanently secured to or form part of the arm B', although I prefer that it should be self-adjusting upon the arm, as described.

To detach the clamp from the joist, it is only necessary to relieve the pressure against the head h, and to then slide the clamp longitudinally in the direction of the arrow 2, until the arm B' has been sufficiently turned to permit the withdrawal of the teeth from the opposite side of the joist.

The principal advantages of my improved clamp are, that it can be readily fastened to and detached from a joist without the aid of screws or other fastenings, which are expensive and liable to get out of order; also, that it is adapted to joists of any width, and that the head is always presented to the wedge at the same angle.

Claims.

1. A joist-clamp, consisting of a frame, B, having a head, h, and serrations or teeth k, and of an arm, B', hinged to the said frame, and having at its outer end a serrated block, l, all substantially as and for the purpose described.

2. The block m, connected to the frame B by an adjustable arm, B', for the purpose set forth.

In testimony whereof, I have signed my name to this specification, in the presence of two subscribing witnesses.

WILLIAM SAILER.

Witnesses:
